Primary Examiner — Ricky Pham

(57) **CLAIM**

The ornamental design for a ceramic cookware, as shown and described.

DESCRIPTION

FIG. 1 is a perspective front view of a ceramic cookware;
FIG. 2 is a front elevation view of the ceramic cookware; the
rear elevation view, the left side elevation view, and the right
side elevation view all being a mirror image thereof;
FIG. 3 is a top plan view of the ceramic cookware; and,
FIG. 4 is a bottom plan view of the ceramic cookware.
